PROCESS OF MANUFACTURING CAR-BURETED WATER GAS

William E. Steinwedell, Cleveland Heights, Ohio,
assignor to The Gas Machinery Company,
Cleveland, Ohio, a corporation of Ohio

Application April 6, 1938, Serial No. 200,449

4 Claims. (Cl. 48—208)

This invention particularly relates to improvements in the well-known methods of manufacturing carbureted water gas in a gas-making set including a generator, a carbureter, a superheater, and a seal, all connected in a well-known manner, and equipped with the usual fixtures such as pipes and valves for supplying suitable media for blasting a fuel bed in the generator, and for making up and down gas-making runs through the fuel bed, and for carbureting the water gas so made. My invention particularly relates to improvements in such processes in which the carburetion is effected by the use of heavy oil, such as bunker oil, and in which a down blasting is effected by admitting the blasting air to the top of the generator.

The invention is particularly applicable for working in that type of a carbureted water gas set in which the hot gas valves for controlling the direction of flow are located respectively, in pipe connections between the top of the generator and the top of the carbureter, and between the bottom of the generator and the top of the carbureter, so that thereby the products of an up-run or a down-run may be selectively conveyed from the top of the generator to the carbureter or from the bottom of the generator to the carbureter, respectively.

The annexed drawing and the following description set forth in detail certain steps illustrating my improved process, these steps constituting, however, but a few of the various series of steps by which the improved process may be carried out.

The figure is a view, partly in elevation and partly in vertical section, of apparatus for manufacturing carbureted water gas by the use of my improved method.

Referring to the annexed drawing, a generator A, a carbureter B and a superheater C constituting carbureting apparatus, and a seal D are connected together in the well-known manner by a pipe E between the top of the generator and the top of the carbureter, a pipe F between the bottoms of the carbureter and superheater, a pipe G leading from the stack C' of the superheater C to the seal D, and a pipe H communicating with the bottom of the generator and with the pipe E adjacent the carbureter B. Pipe I controlled by valve 1' and pipe 2 controlled by valve 2' are provided for feeding air into the bottom of the generator A and the top of the generator A, respectively. A pipe 3 controlled by valve 3' feeds air into the top of the carbureter B. Steam pipes 4 and 8 controlled by valves 4' and 8', respectively, feed into the air pipe I and the air

pipe 2, respectively. A pipe 5 controlled by valve 5' feeds heavy oil into the top of the generator A. The pipe E is controlled by an up-run hot gas valve 7 and the pipe H by a down-run hot gas valve 6. The superheater stack C' is controlled by valve 9.

The manner of using the afore-described apparatus, when working my improved process, consists in first preparing for forward or upward blasting by having all valves closed except the stack valve 9 and the up-run hot gas valve 7. Then the fuel bed in the generator A is blasted with air which is admitted by opening the valve 1', and the resultant blast gases which pass through the connection E from the generator A to the carbureter B are burned by air admitted by opening the blast valve 3', this burning of the blast gases suitably heating the checkerwork in the carbureter B and superheater C. The resultant products are discharged through the open valve 9 of the stack C'.

Then the carbureter blast valve 3' is closed and, in succession, the generator blast valve 1' and the superheater stack valve 9 are also closed, which places the apparatus in condition for an up-run.

The up-run is effected by first opening the steam valve 4' which effects the formation of blue water gas by the passage of the steam through the heated fuel bed, which blue water gas is carbureted by heavy oil admitted by opening the valve 5', which heavy oil is sprayed upon the fuel bed and is cracked and volatilized and mixes with the blue water gas issuing from the fuel bed and is permanently fixed in the heated checkerbrick of the carbureter B and superheater C. The resultant gases pass through pipe G into the seal D. The up-run is terminated by first closing the oil valve 5' and then the up-run steam valve 4'.

Then a down-run is effected by first opening the down-run hot gas valve 6, then closing the up-run hot gas valve 7, and then opening the down-run steam valve 8', which results in the formation of blue water gas by the passage of steam downwardly through the fuel bed, which blue water gas issues from the bottom of the generator and passes by pipe H into pipe E and thence through the carbureter B and the superheater C and through the pipe G into the seal D. The down-run is terminated by closing the steam valve 8'.

Then a down blow is effected by first opening the stack valve 9, and then opening the blast valve 2' which effects a down-blow through the fuel bed of the generator A and the resultant

products therefrom pass into the pipe H and then into the pipe E and thence through the carbureter B and the superheater C and out through the stack valve 9. The down-blow is terminated by closing the blast valve 2'. The up-run hot gas valve 1 is opened, and the down-run hot gas valve 6 closed. Then the apparatus is in the same condition as was originally presented for forward blasting, and a cycle has been completed.

10 Under some conditions when working the improved process which has just been described, it may be deemed essential to effect a short blow-run during the up-blow. This may be effected by closing the superheater stack valve 9 before

15 the bottom generator blast valve 1' is closed and thus terminate the up-blow period by a short blow-run.

Under some conditions, it may be deemed essential to add heavy oil to the fuel bed during part 20 of the down-run, as well as to carburet the blue water gas during the up-run; in which case, the oil valve 5', instead of being closed at the termination of the up-run, can be allowed to remain open during part of the down-run, and then this 25 oil valve 5' can be closed at any desired time after opening the down-run steam valve 8'.

Under some conditions, it may be desired to make a short down-blow run; in which case, the top generator blast valve 2', which furnishes the 30 air for the blast downwardly through the fuel bed, may be opened, after the termination of the down steam run, and before the opening of the stack valve 9, and thus the down-blow gases pass through the connections H and E and thence 35 through the carbureter B and superheater C and thence into the seal D through the pipe G, for a short period, and then the stack valve 9 is opened.

What I claim is:

1. The process of manufacturing carbureted 40 water gas, with the use of heavy oil as the carbureting medium, in a gas-making set including a generator, conduits connecting the top of the generator and the bottom of the generator, respectively, with the carbureting apparatus, and 45 flow-direction control valves disposed in said conduits between the generator and the carbureting apparatus, consisting in first upwardly blasting the fuel bed in the generator with air admitted at the bottom of the generator and burn- 50 ing the blast gases in the carbureting apparatus with air admitted to the latter and passed therethrough then effecting a steam run upwardly through the fuel bed with steam admitted at the bottom of the generator and simultaneously 55 spraying heavy oil upon the top of the fuel bed,

and passing the resultant gaseous products through the carbureting apparatus then effecting a steam run downwardly through the fuel bed with steam admitted at the top of the generator and passing the resultant gaseous products through the carbureting apparatus and then blasting downwardly through the fuel bed with air admitted to the set at the top of the generator and passing the blast gases through the carbureting apparatus.

2. The process, as set forth in claim 1, in which the upward blasting terminates with a short up-blow run after shutting off the air being admitted to the carbureting apparatus.

3. The process, as set forth in claim 1, in which 15 the spraying of heavy oil upon the top of the fuel bed is continued into and through a part of the down steam run.

4. The process of manufacturing carbureted 20 water gas, with the use of heavy oil as the carbureting medium, in a gas-making set including generator, carbureter, and superheater shells, and a seal, conduits connecting said shells and said seal in series, including conduits connecting the top of the generator and the bottom of the generator, respectively, with the carbureter, and flow-direction control valves disposed in said conduits between the generator and the carbureter, consisting in first upwardly blasting the fuel bed 25 in the generator with air admitted at the bottom of the generator and burning the blast gases in the carbureter and superheater with air admitted at the top of the carbureter, and exhausting the waste gases from the set, then effecting a steam run upwardly through the fuel bed with steam admitted at the bottom of the generator and simultaneously spraying heavy oil upon the top of the fuel bed, and passing the resultant 30 gaseous products through the carbureter and superheater to the seal, then effecting a steam run downwardly through the fuel bed with steam admitted at the top of the generator and passing the resultant gaseous products through the carbureter and superheater to the seal, then effecting a short down blow run through the fuel bed 35 with air admitted to the set at the top of the generator and passing the resultant products through the carbureter and superheater to the seal, and then continuing the said down blow 40 through the fuel bed and passing the blast gases through the carbureter and superheater and thence exhausting them from the set.

WILLIAM E. STEINWEDELL. 55

CERTIFICATE OF CORRECTION.

Patent No. 2,216,056.

September 24, 1940.

WILLIAM E. STEINWEDELL.

It is hereby certified that error appears in the printed specification of the above numbered patent requiring correction as follows: Page 1, second column, line 26, for "The" read --This--; page 2, first column, line 5, for "The" read --Then the--; line 42, claim 1, before "conduits" insert the words and comma --carbureting apparatus,--; line 52, after "through" insert a comma; and second column, lines 2 and 6, same claim 1, after the word "apparatus" insert a comma; line 23, claim 4, strike out "and" first occurrence; and that the said Letters Patent should be read with this correction therein that the same may conform to the record of the case in the Patent Office.

Signed and sealed this 29th day of October, A. D. 1940.

Henry Van Arsdale,
(Seal) Acting Commissioner of Patents.
